UNITED STATES PATENT OFFICE.

HARRY PRESCOTT SIMPSON, OF PITTSBURG, PENNSYLVANIA.

DESIGN FOR A GAS-STOVE LEG.

SPECIFICATION forming part of Design No. 34,723, dated July 2, 1901.

Application filed February 20, 1901. Serial No. 48,199. Term of patent 7 years.

To all whom it may concern:

Be it known that I, HARRY PRESCOTT SIMPSON, a citizen of the United States, residing at Pittsburg, in the county of Allegheny and State of Pennsylvania, have invented and produced a new and original Design for a Gas-Stove Leg, of which the following is a specification, reference being had to the accompanying drawings, forming part thereof.

Figure 1 shows a perspective view of a gas-stove leg embodying my invention; Fig. 2, a longitudinal section on line $x-x$ of Fig. 1, and Fig. 3 a cross-section on line $y-y$ of Fig. 1.

The leading and characteristic features of my design consist of the form of leg for a gas-stove, as shown, in which the leg comprises a body portion having raised portions or ribs, a depression or hollow between said ribs, a flange or shoulder extending upwardly from the body portion, and a portion extending downwardly from the body and terminating in an outwardly-curved portion or foot.

Referring to the drawings, the leg comprises the curved body portion 1, having raised

portions or ribs 2 at the sides and a depression 25 or hollow portion 3 at the center. Below the raised portions an inwardly-curved portion 4 extends downwardly from the body and terminates in an outwardly-swelled rounded portion or part which forms the foot 5.

Projecting upwardly from the upper end of the body portion is a flange or shoulder 6, which is of the same width as the body and extends therefrom substantially at right angles thereto.

Having thus described my design, which consists rather in the general contour of the stove-leg as shown than the ornamentation thereof, what I claim is—

The design for a gas-stove leg, substantially as shown and described.

In testimony whereof I have signed my name to this specification in the presence of two subscribing witnesses.

HARRY PRESCOTT SIMPSON.
